[57] **CLAIM**

The ornamental design for a halogen quartz lamp radiant heating module, as shown.

DESCRIPTION

FIG. 1 is a top plan view of a halogen quartz lamp radiant heating module, showing my new design;

FIG. 2 is a bottom plan view thereof;

FIG. 3 is an elevational view of one side thereof;

and,

FIG. 5 is an elevational view of one end, the elevational view of the opposite end being a mirror image thereof.
